UNITED STATES PATENT OFFICE.

JAMES C. WRIGHT, OF COLORADO SPRINGS, COLORADO, ASSIGNOR OF ONE-HALF TO
T. L. RIPPEY, OF DALLAS, TEXAS.

ROCK-DRILL.

1,218,149.

Specification of Letters Patent.

Patented Mar. 6, 1917.

Application filed March 8, 1916. Serial No. 82,984.

To all whom it may concern:

Be it known that JAMES C. WRIGHT, a citizen of the United States, residing at 515 West Monument street, Colorado Springs, in the county of El Paso and State of Colorado, have invented certain new and useful Improvements in Rock-Drills, of which the following is a specification.

My invention relates to certain new and useful improvements in rock drills and pertains more particularly to that type having an automatic feed mechanism, the primary aim being to provide such a machine in which the feed is controlled or governed by the hammer.

Certain mechanical feeds heretofore used are objectionable because of the fact that the feed is constant even when the drill is jammed or stuck with great injury resulting.

An important object of the present invention is, therefore, to provide a feed mechanism which will remain at rest, when the bit is being jammed, and, when the bit is freed, the automatic feed will resume its operation.

The invention, further, comprises means for automatically changing the hammer blow from a heavy to a light one, when the bit is being jammed, this being accomplished by the shortening of the hammer stroke.

Another aim resides in an improved chuck rotating means which will yield or break when the bit is unduly resisted.

The invention further resides in an improved support for the drill and also in the features of construction, arrangements and combinations of parts hereinafter described and claimed, reference being had to the accompanying drawings wherein like characters of reference designate corresponding parts throughout the several views of which—

Figure 1 is a side elevation of my improved rock drill;

Fig. 2 is an elevation of the chuck end of the drill the parts in front of the ratchet being removed to clear the view thereof;

Fig. 3 is a similar view of the opposite end of the machine;

Fig. 4 shows in longitudinal vertical section the interior workings of the mechanism;

Fig. 5 is a transverse section on line 5—5

of Fig. 1 through the chuck rotating mechanism;

Fig. 6 is a similar view on line 6—6 of Fig. 1 showing the hammer actuating cams;

Fig. 7 is a side elevation of my improved support on which I prefer to mount the drill; and

Fig. 8 is a section through the socket, the view being taken on line 8—8 of Fig. 1.

The casing 1 of the drill is provided with a chamber 2 in which reciprocates the hammer 3. The shank or stem 4 of the hammer extends rearwardly through the casing and its removable head 5 between which and nuts 6, threaded on the extremity of the shank 4, coils a cushion spring 7. Within the casing, the shank is formed with a shoulder 8 on which one end of a coiled compression spring 9 seats, the opposite end bearing on said removable head 5.

In advance of the shoulder 8, the hammer shank is provided with a pair of oppositely extending lugs 10 which are held by spring 9 against the active faces of the cams 11, said cams being spaced to receive the shank therebetween (Fig. 6) and are fixed on a transverse shaft 12 journaled in and extending at each end from the casing. On one projecting end of the shaft is a gear 13 meshing with a larger drive gear 14 which is fixed on a second shaft 15 journaled in the casing.

Each end of this second shaft 15 carries a removable and adjustable handle 16 so that should it be necessary to operate close to a wall, the handle on that side may be removed.

In the forward part of the casing, the bit chuck 17 is rotatably disposed and provided with a ratchet 18 and a suitable water supply 19 for cleaning the bit 20. Arranged in the inner end of the chuck is a pin 21 slidable against the bit by being struck by the hammer and retained within its chamber by a removable cap 22.

A spring actuated pawl 23 engages the ratchet 18 to prevent back movement thereof, forward rotation being imparted to the ratchet and its chuck by a dog 24 yieldably mounted on a carrier 25 which is slidable vertically in a tangential pocket 26 of the casing. A two-part lever 27, which is

pivoted to the casing at 29, is connected at one end to the carrier 25, and has its opposite end slotted, as at 30, to slidably receive a strap block or shoe 31. An eccentric 32, 5 fixed on the opposite end of shaft 12 to which the gear 13 is attached, is received by the strap block 31.

The operation of the machine thus far described is as follows: The shaft 15 is rotated by either or both handles 16 and, 10 through gears 13 and 14, the shaft 12, bearing a counter-balance or fly wheel 33, is revolved. The cams 11, in revolving, slide the hammer backwardly against the tension of spring 9 so that when the lugs 10 ride off the cams at points 34 the compressed spring will immediately force the hammer against the percussion pin 21 which transmits the blow to the bit. The hammer is cushioned 15 at the termination of its active stroke by the spring 7.

During this operation, the eccentric 32 oscillates the section 27' of lever 27 and, 20 through lever section 27'', reciprocates the carrier 25 to intermittently rotate the drill chuck. Each lever section is pivoted to the pin 29 and has a depending finger 35. An expansion spring 36 connects the fingers 35 to normally constitute an operative connection 25 between the lever sections whereby, should the drill stick, the spring will yield to prevent the chuck from rotating. Thus, in effect, lever 27 is a breakable drive between the eccentric and carrier.

30 The casing 1 is formed with a depending, inverted T-shaped web 37 slidably arranged in the track grooves 38 of a channeled base 39. A feeding screw 40 is journaled in the base and engages with a nut part 41 depending from the web 37 whereby on rotating the feeding screw the drill casing or carriage 1 will slide in the tracks 38.

Although the feed of the drill carriage may be accomplished by manually rotating 45 the screw shaft 40, with the crank handle 42, I prefer to make the feed automatic. Certain mechanical feeds continue to operate, when the bit is jammed and inoperative, causing great damage and injury to the machine. This defective feed is due, in part to the fact that the hammer in no way enters into the feed operation.

By my invention, the hammer controls the feed of the drill carriage and when the 50 stroke of the hammer is not full or complete the feed mechanism is allowed to remain at rest.

On the screw shaft 40 is fixed a gear 43 which meshes with a gear 44 fixed to one 55 section 45 of an extension shaft. This shaft section is journaled on the base and teleoscopically receives the component shaft section 46 which is splined or otherwise secured thereto for relative sliding movement 60 only. This second shaft section is journaled

in a suitable bracket extension 47 of the carriage. Fixed on the shaft section 46 is a ratchet 48 retained against reverse rotation by a spring actuated pawl 49.

A supporting link 50, swingingly disposed on shaft 46, pivotally carries a hooked pawl 51 which engages with the ratchet 48 and is provided with an arm or lug 52 extending beneath the carriage. A spring 53 normally holds the pawl 51 engaged with the ratchet, depression of the arm 52, and the consequent rotation of the ratchet, being effected by a blade-like trip 54 which is fixed to the hammer, as at 55. The extreme forward end of the trip is formed 80 with a cam edge 56 to ride and depress the arm 52. The feed is geared to advance the carriage at a greater speed than the bit will operate.

From Fig. 4, it will be noted that the trip 85 54 does not operate until almost the very end of the hammer stroke is reached. Therefore, if the bit is jammed or the carriage is advanced thereon, the pin 21 will be pushed toward the hammer by the bit, 90 and the hammer stroke will be shortened to such an extent as to prevent the proper operation of a trip 54. The bit, however, is continually being struck by the hammer so that, when the former is free or has operated to the depth permitted by the arrested 95 position of the carriage, the trip will again actuate the feed.

One form of support I may use with this improved drill is depicted in side elevation 100 in Fig. 7 and comprises a tubular body 57 having a foot 58 at one end and a cross head 59 fixed at its opposite end, the ends of the cross head each having a pivotal nut 60 through which is threaded adjusting and 105 setting screws 61. These screws may be operated in any suitable manner and carry swivel bearing blocks 62.

Adjustably fixed on the body 57 is a socket 63 which receives a depending stud 110 64 on the base 39. The socket is formed with a slot 65 through which passes a screw bolt 66. This bolt is carried by an arcuate plate 67 whose inner face is serrated to firmly grip the socket when the bolt is tightened, the latter being threaded in the base stud as illustrated in Fig. 8.

After the support 57 has been positioned between opposing walls, as in a mine, the drill may then be angularly adjusted to any 120 desired position which is maintained by tightening screw bolt 66 to clamp the stud 64 to the socket. The drill is then ready for operation.

The drill is entirely automatic the operator only supplying the motive power. If the bit sticks the feed and rotation of the chuck are brought to a standstill although the hammer continues its movement to a limited degree. This continued operation 125 130

of the hammer will eventually loosen the bit from the rock and the automatic operation and feed resumed.

The support 57 may be supported between walls having irregular surfaces since the swiveled bearing blocks 63 will readily adapt themselves to the such irregularities.

What is claimed is:

1. In a rock drill, the combination with a base, of a carriage arranged to slide upon the base, a threaded shaft engaging the carriage for feeding the carriage, a hammer, a bit movably supported by the carriage in the path of the hammer, means for operating the hammer, a telescopic shaft arranged parallel with the said threaded shaft, gearing connecting the said telescopic and threaded shafts at the rear of the base, a ratchet and pawl device arranged at the forward end of the base beyond the path of the body of the hammer for operating the telescopic shaft, and a member carried by the hammer and projecting from the hammer for operating the said ratchet and pawl device by the forward movement of the hammer.

2. In a rock drill, the combination with a base, of a carriage arranged to slide upon the base, a threaded shaft arranged longitudinally within the base below the carriage and engaging the carriage for feeding the carriage, a hammer, a bit movably supported by the carriage in the path of the hammer, means for operating the hammer, a telescopic shaft arranged upon one side of the base and parallel with the said threaded shaft, means for transmitting the rotary movement of the said telescopic shaft to the said threaded shaft, a ratchet upon the said telescopic shaft, a pawl engaging the said ratchet and arranged at the forward end of the base beyond the path of the hammer for

rotating the said telescopic shaft, and a trip arm connected with the lower side of the hammer and projecting forwardly beyond the hammer, the said pawl having a portion arranged to engage the said trip arm whereby the said pawl and ratchet are operated and the said telescopic shaft is rotated.

3. In a drill, a base, a threaded shaft journaled thereon, a second shaft journaled on the base and gearing with the first shaft, a carriage, a bit carried by the carriage, a hammer for actuating the bit, a shaft journaled on the carriage and slidably connected to the second shaft for rotating the latter, a ratchet fixed on the third shaft, a movable pawl engaged with the ratchet for intermittently rotating the same, and a trip carried by the hammer to move the pawl.

4. In a rock drill, the combination with a base, of a carriage sliding thereon, a longitudinally movable hammer upon the carriage, means for operating the hammer, a threaded carriage-feeding shaft and a telescopic shaft extending parallel with the axis of the hammer, the said threaded shaft engaging the carriage, means connecting the said shafts whereby the rotation of one is communicated to the other, shaft-rotating devices borne by the said base and the said telescopic shaft and arranged to act upon the said telescopic shaft, and a member moved by the hammer whereby the said shaft-rotating devices are engaged and operated.

In testimony whereof I affix my signature in the presence of two witnesses.

JAMES C. WRIGHT.
